UNITED STATES PATENT OFFICE.

HAROLD A. EKLUND, OF TULSA, OKLAHOMA.

OIL INJECTOR.

Application filed September 14, 1922. Serial No. 588,228.

To all whom it may concern:

Be it known that I, HAROLD ANDREW EKLUND, a citizen of the United States, residing at Tulsa, in the county of Tulsa and 5 State of Oklahoma, have invented new and useful Improvements in Oil Injectors, of which the following is a specification.

This invention relates to devices for containing and injecting oil or other lubricants into motors, parts of machinery or other parts to be lubricated, and particularly to a device for injecting oil of more or less heavy or viscous character through the lubricant inlets of motors or parts of machinery to be lubricated, and one object of the invention is to provide an oil injector which is simple of construction, reliable and efficient in action, not liable to get out of order, and by means of which oil of greater 10 or less specific gravity may be easily and quickly injected through the lubricant inlet of the motor or part of machinery to which the oil is to be supplied.

A further object of the invention is to 25 provide an oil injector which will operate for long periods without cleaning or repairs, which may be constructed, installed and operated at small expense, which ensures the positive introduction of the oil 30 in a cleanly manner to the part to be supplied, and which enables measured quantities of oil to be supplied with extreme accuracy, thus ensuring the delivery to the customer of the right amount of oil he pays for.

With these and other objects in view, the 35 invention consists of the features of construction, combination and arrangement of parts, hereinafter fully described and claimed, reference being had to the accompanying drawing, in which:—

Figure 1 is a central vertical section through an oil injector constructed in accordance with my invention.

Figure 2 is a horizontal section through 45 the same.

Referring to the drawing, 1 designates an outer containing casing or cylinder, closed by top and bottom concavo-convex heads 2 and 3 and sub-divided by an internal partition 4 into an upper air pressure chamber 5 and a lower oil containing and pressure chamber 6. The partition 4 closes the two chambers 5 and 6 against communication, except as hereinafter described, and 50 is securely united at its periphery to the wall of the casing 1 against any possibility of

leakage of pressures between said chambers. The cylinder 1 is made as a whole of metal or other suitable material of adequate strength to sustain the desired working 60 pressures.

Arranged within the air chamber 5 is a primary oil reservoir tank or chamber 7. This tank 7 is of less diameter than the chamber 5 and terminates at its lower end a desired distance above the partition 4. At its upper end the tank 7 projects outwardly through an opening in the head 2 and is provided with a removable cover 8. At the point of passage of the tank 7 through the head 2 the joint is securely sealed against any possibility of the escape of air pressure from the chamber 5. The tank 7 is of a capacity to contain, up to a certain level, a predetermined quantity or amount 70 of oil in gallons or other units. This oil may be supplied to the tank 7 through the open top of said tank when the cover 8 is removed. Extending vertically within the tank 7 is an indicator 9, consisting preferably of a strip of metal or other material extending upwardly from the bottom of the tank and terminating at the maximum oil level therein. This strip may be fixed in position in any suitable manner and is provided with graduations or indications 10, indicating the amount of oil contained in the tank at given levels. The graduations on this indicator strip may be inspected at any time upon removal of the cover 8. 80

Connecting the lower end of the tank 7 with the oil pressure chamber 6 is an oil feed pipe or conduit 11 having arranged therein a check valve 12, which valve is adapted to open, when the chamber 6 is 85 empty and pressure removed therefrom, to permit oil to flow from the tank 7 to the chamber 6 to fill the latter, the valve 12 closing to prevent any possibility of back-flow of the oil. The chamber 6 may be, 90 and preferably is, a measuring chamber having a given capacity, or adapted to hold a measured quantity of oil or lubricant to be dispensed, so that each time said chamber 6 is emptied an accurate amount of oil or 95 lubricant will be delivered. The oil is discharged from the chamber 6 through a flexible discharge pipe 13 having a terminal discharge nozzle 14 and a controlling and cut-off valve 15.

Connecting the air pressure chamber 5 with the extreme top portion of the oil

pressure chamber is a pressure feed pipe 16. This pipe communicates at its upper end with the chamber 5 and with an air supply pipe 17 having a controlling and cut-off valve 18 therein. The pipe 17 may lead from a pump or other source of compressed air supply, or may be adapted for connection with a flexible hose pipe leading from such source of supply, whereby the chamber 5 may be recharged with air to maintain a given working air pressure therein. A gage 19 is provided at the top of the pipe 16 so that the internal pressure within the tank 5 may at all times be ascertained and indicated. At the lower end of pipe 16 is an air relief and level indicating valve 20, the valve member of which may be provided with a depressible stem 21 and a valve closing spring 22, by means of which stem the valve may be manually opened and held open for a desired period, the spring serving to automatically close the valve when the stem is released. Arranged in the pipe 16 between the air supply connection 17 and the said valve 20 is a pressure feed valve 23 which may be opened and closed to control communication between the air pressure chamber 5 and the oil pressure chamber 6. In the operation of the device, as thus constructed, the tank 7 is charged with oil which flows therefrom through the pipe 11 into the chamber 6, the supply being continued until the oil reaches the maximum level in the tank 7. While the chamber 6 is being filled with oil, the stem 21 of valve 20 is held depressed to allow the air in said chamber 6 to vent to the atmosphere, said stem being released to allow said valve to close at the moment oil begins to show at the valve outlet, giving an indication that the chamber 6 has been completely filled. Valve 18 is now opened, while the valve 23 remains closed, to charge the chamber 5 with compressed air to the desired pressure, after which valve 18 is closed. The apparatus is now ready for operation for the dispensation of oil, and in discharging the measured quantity of oil from the chamber 6 the valves 15 and 23 are opened, the valve 23 allowing compressed air to pass from the chamber 5 to the chamber 6 to expel the oil outwardly through the pipe 13 and discharge nozzle 14. Valves 15 and 23 are then closed and valve 20 again opened to allow escape of the remaining air pressure from chamber 6 and said chamber to refill with oil from the tank 7, after which valve 20 is allowed to close, thus priming the apparatus in readiness for a subsequent oil discharge action. The nozzle 14 may be of such size as to allow it to be conveniently entered into the filling hole of the motor or other part of machinery to be supplied with the lubricant, whereby the oil will be discharged in a cleanly manner and under a

required pressure to the elements to be supplied. Measured quantities of oil may thus be delivered in a ready and convenient manner and successive discharges of measured quantities made, when required, to make up any given amount.

As before stated, upon removal of the cover 8 the indicator 9 within the tank 7 may be viewed, enabling the operator to tell exactly the amount of oil contained in the chamber 7 and tank 6 at any time. If the quantity contained is known, or the indicator 9 inspected before a discharge action, assuming that less than the measured quantity of oil in chamber 6 is to be expelled, the operator may determine the amount of oil expelled by again inspecting the indicator 9, from which he can readily calculate from the reading of the levels given before and after the discharge action, the exact amount of oil dispensed.

From the foregoing description, taken in connection with the drawing, the construction and mode of operation of my improved oil dispensing device will be readily understood, and it will be seen that it provides a device of this character which is simple of construction, reliable and efficient in action, and contains no complicated parts or packings liable to get out of order or to require frequent cleaning or repairs. Also it will be seen that it provides a device by means of which a measured quantity of more or less oil may be dispensed and positively forced into the oil receptacle of the motor or element to be supplied. Furthermore, it will be seen that it provides a device which is easily handled and cleanly in operation and in which the oil is protected at all times against the access of dirt or other foreign particles. The device may be a fixture in a garage or other oil dispensing establishment, or it may be mounted upon a wheeled support so as to be readily movable from place to place for use.

Having thus fully described my invention, I claim:

1. An oil injector comprising an air pressure chamber, an oil pressure chamber arranged below the air pressure chamber, an oil container extending into the air pressure chamber, a check valved connection between the oil container and the oil pressure chamber for the flow of oil by gravity from one to the other, a valved discharge outlet from the oil pressure chamber, and means for conducting air from the air pressure chamber to the oil pressure chamber for an oil discharging action.

2. An oil injector comprising an air pressure chamber, an oil pressure chamber arranged beneath the air pressure chamber, a valved discharge outlet from the oil pressure chamber, an oil container partially enclosed within the air pressure chamber and

having an open upper end projecting outwardly through the top of said air pressure chamber, a closure for the open upper end of the oil container, a check valved conductor between the oil container and the oil pressure chamber for the flow of oil by gravity from one to the other, and means for supplying air under pressure from the air pressure chamber for the discharge of oil

10 from the oil pressure chamber.

3. An oil injector comprising an air pressure chamber, an oil pressure chamber arranged beneath the air pressure chamber, a valved discharge outlet from the oil pressure chamber, an oil container above the oil pressure chamber, a check valved conductor between the oil container and air pressure chamber for the flow of oil by gravity from one to the other, an air supply pipe connecting the air pressure chamber with the top of the oil pressure chamber, an air relief and oil level indicating valve in said pipe, and a closure and cut-off valve between the

air pressure chamber and said relief and indicator valve.

4. An oil indicator comprising an air pressure chamber, an oil pressure chamber arranged beneath the air pressure chamber, a valved discharge outlet from the oil pressure chamber, an oil container arranged above the air pressure chamber, a check valved connection between said container and oil pressure chamber for the flow of oil by gravity from the former to the latter, an air feed pipe connected at its upper end with the air pressure chamber and its lower end with the top of the oil pressure chamber, a valved air supply pipe connected with the upper end of said feed pipe, an air relief and oil level indicating valve in the lower end of said air feed pipe, and a closing and cut-off valve in said pipe between said upper end and said air relief and indicator valve.
